[57] CLAIM

The ornamental design of a distribution unit for multiple controllers for video games, as shown and described.

DESCRIPTION

FIG. 1 is a top view of the distribution unit for multiple controllers for video games embodying my new design;

FIG. 2 is a bottom view thereof;

FIG. 3 is a front view thereof;

FIG. 4 is a rear view thereof;

FIG. 5 is a right side view thereof;

FIG. 6 is a left side view thereof;

FIG. 7 is a sectional view of the distribution unit as taken along line 7—7 of FIG. 1, but with the internal structure eliminated for purposes of illustration;

FIG. 8 is a sectional view of the distribution unit as taken along line 8—8 of FIG. 1, but with the internal structure eliminated for purposes of illustration; and,

FIG. 9 is a perspective view thereof.

The broken lines showing hand held controllers, video game control and conduits in FIG. 9 is for illustrative purposes only and forms no part of the claim.

FIG. 2

FIG. 1

FIG. 4

FIG. 3

FIG. 5

FIG. 6

FIG. 8

FIG. 7

FIG. 9
